RADIO APPARATUS

George Zindel, Jr., Fox Chase Manor, Pa., assignor to Philco Corporation, Philadelphia, Pa., a corporation of Pennsylvania

Application March 4, 1948, Serial No. 13,013

10 Claims. (Cl. 250—14)

1

The present invention relates to radio apparatus and, particularly, to radio receivers. More specifically, the invention has to do with improvements in the construction and assembly of parts which go into the making of radio receivers.

It is the primary object of the invention to provide a novel disposition and relation between a radio chassis and a loud-speaker and, also, to provide a novel arrangement and association of these parts with elements of a cabinet so as to produce a self-contained radio receiver of distinctive compact structure. To that end, the invention utilizes an organization in which the chassis and the speaker are disposed and related in such a manner as to provide a compact unit, and in which cabinet-forming members are so arranged and associated with such unit as to produce a finished unitary assembly, the overall dimension of which does not greatly exceed that of said unit.

Another object of the invention is to provide a radio receiver of the above mentioned type, which is particularly characterized by the simplicity of its construction and by the economical use of materials employed for its production. Especially, the invention makes it possible to reduce, appreciably, the number of parts necessary for complete assembly of the radio receiver and to utilize inexpensive cabinet parts which can be readily put together and associated with the radio chassis to house the same.

Another and more specific object of the invention resides in the provision of a self-contained radio receiver in which certain parts are advantageously employed to perform several useful functions in the assembly and in the operation of such a receiver and, thus, effectively contribute toward the provision of a simplified compact unitary structure. For example, in accordance with this object of the invention, the loud-speaker mounting structure is adapted for cooperative association with the indicating means of the tuning device to guide such means in its movement, and a part which serves to complete the cabinet also serves to provide the antenna for the receiver.

These and other objects, and the manner in which they are obtained, will be fully understood from the following description based on the accompanying drawings which illustrate a preferred embodiment and in which:

Figure 1 is a front elevation of a radio receiver constructed in accordance with the invention;

Figure 2 is an enlarged view similar to Figure

2

1, with certain parts removed and other parts broken away to illustrate certain characteristic structural features;

Figure 3 is an enlarged sectional view, taken substantially along line 3—3 of Figure 1; and

Figure 4 is an exploded view, in perspective and on an enlarged scale, showing the construction and relationship of the essential parts of the radio receiver.

Referring more particularly to the drawings, the radio receiver, as shown, comprises a cabinet or casing structure indicated, generally, at 10 (see Figure 1) and a radio chassis designated, in its entirety, by the reference numeral 11 (see Figures 2 and 4).

The chassis includes a mounting support 12 and the usual main component parts of a receiver, such as tubes 13, I.-F. transformers 14, tuning or variable condenser 15, combined on-off switch and volume control 16, and power transformer 17. The customary wiring and various small parts, such as resistors and capacitors, are suitably arranged inside the mounting support 12. This support, as shown, takes the form of a box-like member with a removable cover 18. The mentioned main component parts are mounted on the side walls of said member and extend outwardly from said walls, in a plane substantially paralleling the plane of the cover 18, so as to project substantially radially about the mounting support, as more clearly shown in Figure 2.

The cover 18 is provided with a centrally disposed outwardly projecting flange 19. This flange provides an opening registering with the mouth of a loud-speaker 20 which, in accordance with the invention, is advantageously mounted in and disposed axially of said box member, the usual speaker rim (not shown) being connected to the cover 18 by means of suitable securing elements 21a. A speaker-protecting grill 21 is suitably associated with the flange 19 to extend over the opening provided thereby. By associating the chassis and the speaker in the above described manner, said chassis and speaker constitute a unit which can be readily handled for assembly with the cabinet or casing structure 11.

As represented in the drawings, the cabinet or casing structure includes a pair of confronting symmetric panels 22 and 23 which are constructed of suitable material, such as wood or composition board. One panel 22 provides the back of the cabinet, and the other panel 23 provides the front of the cabinet. The chassis-

speaker unit is suitably fixed on the back panel 22 to be thereby supported between the panels. The other or front panel 23, has a centrally disposed opening 24 which, as seen in Figure 1, registers with the speaker grill 21 to expose the same. The front panel is further provided with an aperture 25 (Figure 4) through which actuating shaft 26 of the variable condenser is adapted to extend, and with an aperture 27 through which actuating shaft 28 of the combined switch and volume control is adapted to extend. As represented in Figure 1, the usual manually operable knobs 29 and 30 are provided on the extended ends of the actuating shafts to operate the same.

The back panel 22 and the front panel 23 are advantageously retained in assembled relationship by means of a split annular band 31 which, for that purpose, is provided with peripheral channel portions 32 and 33. As more fully illustrated in Figure 3, one channel portion 32 engages the marginal edge portion of rear panel 22, and the other channel portion 33 engages the marginal edge portion of the front panel 23. The extremities of band 31 terminate with angularly depending projections 34 which are adapted to be connected, by means of suitable securing elements 35, to opposite ends of a block 36. This block is fixed on a base 37 for the receiver cabinet structure. Relative rotational movement or displacement between the panels is prevented by means of extensions 38 on panels 22 and 23, which extensions are adapted for abutting engagement with the ends of channeled portions of band 31. It is to be noted that the length of block 36 and the dimension of panel extensions 38 are such that when the angular projections 34 of the band are properly connected with the ends of the block, said band clampingly embraces the panels and thus serves not only to connect the panels but, also, to complete the cabinet or casing structure.

In practice, the band 31 is further adapted to serve as a single turn high "Q" loop antenna and is preferably constructed of aluminum, although any other suitable material may be employed. Leads 39 are conveniently taped to the end portions of the loop and connected with suitable terminals 40 on the chassis.

The front panel 23 of the cabinet or casing is provided with a suitable scale 41 arranged about a part of the central opening in said panel. This scale cooperates with a movable pointer element 42 to give visual indication of the tuning of the radio to resonance with a desired station in response to adjustment of the variable condenser 15. For that purpose, and in accordance with the invention, use is advantageously made of the flange 19 on cover 18 of the chassis. As more clearly shown in Figure 2, the outer cylindrical surface of the flange provides a track on which a cord 44 rides, a spring 45 being included in the length of the cord to maintain it under proper tension. The cord is connected with the pointer element 42 and is passed in engagement with a pulley 46 which is rigidly affixed on the actuating shaft 26 of the variable condenser. The pointer element is constructed in such a manner as to pass and to slide between adjacent edges of the speaker grill 21 and of the front panel 23. By means of the above described arrangement, it will be understood that rotation of the shaft 26 through manipulation of the knob 29 causes the cord 44 to slide on the outer surface of flange 19

and, in turn, movement of the cord causes the pointer element 42 to slide along the scale 41.

From the foregoing description, it will be appreciated that the invention provides a simple and characteristic arrangement which makes it possible to construct a compact self-contained radio receiver which, when standing on its base 37, occupies little space on a table or on a shelf, or like supports. It will, of course, be understood that if desired, the receiver may be hung on a wall or like surfaces. It will also be appreciated that a construction according to the invention is most advantageous in that a part serving to complete the cabinet or housing structure can be employed as an antenna for the receiver, and in that the peculiar relationship of the speaker and its grill with the associated portions of the cabinet structure provides adequate and simple arrangement for guiding the movement of the indicating element of the tuning device.

I claim:

1. A radio receiver comprising a radio chassis including a box-like member, a speaker mounted in said member, and a cabinet enclosing said chassis; said cabinet including a pair of confronting panels between which the chassis is mounted, and an antenna structure arranged between the panels and cooperating therewith to complete the cabinet.

2. A radio receiver comprising a radio chassis including a box-like member having a cover provided with an opening, a speaker enclosed in said member and having its mouth in registry with said opening, a cabinet including a back panel and a front panel between which the chassis is mounted, the front panel having an opening disposed to register with the speaker mouth, and an antenna structure arranged between the panels and cooperating therewith to complete the cabinet.

3. A radio receiver comprising a radio chassis including a box-like member having a cover provided with a substantially centrally disposed and outwardly projecting flange defining an opening, a speaker enclosed in said member and having its mouth in registry with said opening, a cabinet structure including a pair of confronting substantially circular panels, one panel forming the back of the cabinet and supporting the chassis, the other panel forming the front of the cabinet and having an opening disposed to register with the opening in said cover, and a generally annular band arranged about the marginal edges of said panels to complete the cabinet, said band providing a single turn high "Q" loop antenna for the receiver.

4. A radio receiver comprising a radio chassis including a mounting support and radio component parts mounted to extend outwardly and substantially radially of said support, a speaker arranged axially of said support, and a pair of confronting panels between which the chassis is mounted, said panels extending substantially perpendicularly to the axis of the speaker.

5. A radio receiver comprising a radio chassis including a mounting support and radio component parts, said support consisting of a box-like member and said parts being arranged on the side walls of said member to extend outwardly and substantially radially therefrom, a speaker mounted in and disposed axially of said member, and a pair of confronting panels between which the chassis is mounted, said panels extending substantially perpendicularly to the axis of the speaker.

6. A radio receiver comprising a radio chassis including a mounting support and radio component parts mounted to extend outwardly and substantially radially of said support, a speaker arranged axially of said support, a pair of confronting panels between which the chassis is mounted, said panels extending substantially perpendicularly to the axis of the speaker, and an antenna structure arranged in cooperative relationship with said panels to provide a casing for said chassis.

7. A radio receiver comprising a radio chassis including a mounting support and radio component parts, said support consisting of a box-like member and said parts being arranged on the side walls of said member to extend outwardly and substantially radially therefrom, a speaker mounted in and disposed axially of said member, a pair of confronting panels between which the chassis is mounted, said panels extending substantially perpendicularly to the axis of the speaker, and a band between and in engagement with the marginal edges of the panels to interconnect the same, said band providing a single turn high "Q" loop antenna for the receiver.

8. A radio receiver comprising a radio chassis including a box-like member having a cover provided with a substantially cylindrical outwardly projecting flange defining an opening, a speaker enclosed in said member and having its mouth in registry with said opening, a cabinet structure including a pair of panels between which the chassis is mounted, one panel having an opening disposed to register with said opening defining flange, and tuning indicator means for the receiver; said means having a flexible driving element arranged for riding engagement with said flange, a pointer element connected with said driving element and passing through the opening in said one panel, and a scale arranged on said one panel in cooperative relationship with said pointer element.

9. A radio receiver comprising a radio chassis including a box-like member having a cover provided with a substantially cylindrical outwardly projecting flange defining an opening, a speaker enclosed in said member and having its mouth in registry with said opening, a speaker-protecting grill associated with said flange to extend over said opening and speaker mouth, a cabinet structure including a pair of panels between which the chassis is mounted, one panel having an opening disposed to register with said grill to expose the same, and tuning means for the receiver; said tuning means having a flexible driving element arranged for riding engagement with said flange, a pointer element passing between adjacent edges

of the speaker grill and associated panel, and a scale on the latter panel in cooperative relationship with said pointer element.

10. A radio receiver comprising a chassis including a box-like member having a cover provided with a substantially cylindrical outwardly projecting flange defining an opening, a speaker enclosed in said member and having its mouth in registry with said opening, a speaker-protecting grill associated with said flange to extend over said opening and speaker mouth, a cabinet structure including a pair of confronting substantially circular panels, one panel forming the back of the cabinet and supporting said chassis, the other panel forming the front of the cabinet and having an opening in registry with said grill to expose the same, a split generally annular band having peripheral channel portions in engagement with the marginal edges of the panels to interconnect the same and to complete the cabinet, said band providing a single turn high "Q" loop antenna for the receiver, and tuning means for the receiver; said tuning means having a flexible driving element arranged for riding engagement with said flange, a pointer element passing between adjacent edges of the speaker grill and front panel and connected with the driving element to be driven thereby, and a scale arranged on said front panel in cooperative relation with said pointer element.
